UNITED STATES PATENT OFFICE.

FRED L. CORSON, OF ROCHESTER, NEW HAMPSHIRE.

STRIP-GUIDE FOR SEWING-MACHINES.

1,093,540.

Specification of Letters Patent. Patented Apr. 14, 1914.

Application filed March 9, 1912. Serial No. 682,738.

To all whom it may concern:

Be it known that I, FRED L. CORSON, a citizen of the United States, and a resident of Rochester, in the county of Strafford and **5** State of New Hampshire, have invented a new and Improved Strip-Guide for Sewing-Machines, of which the following is a full, clear, and exact description.

My invention relates to devices for the **10** manufacture of inner soles for shoes, and it has for its object to provide means for attaching ribbed canvas to the inner soles, which makes it unnecessary to channel the inner soles as is now the custom, and permits **15** the use of inexpensive leather for the construction of the inner soles. While a saving is made in the cost of manufacture, the inner soles as constructed by me are much stronger than those hitherto used. **20** The device, which is preferably attached to a sewing machine, holds the ribbed portion of the canvas between the sides of the canvas and in position, while it spreads the sides of the canvas, and holds them **25** against the inner sole, while it is sewed thereto.

Additional objects of the invention will appear in the following complete specification, in which the preferred form of the **30** invention is disclosed.

In the drawings similar characters of reference indicate corresponding parts in all the views, in which—

Figure 1 is a perspective view showing how **35** my device is used; Fig. 2 is a side sectional elevation of my device; Fig. 3 is an end view of the front of the device; Fig. 4 is a transverse sectional view of the device, showing the passageway with the channel through **40** which the sides and the rib of the canvas travel; Fig. 5 is a transverse sectional view showing the passageway with the channel and the dividing wheel for separating the canvas at the sides of the ribbed portion; **45** and Fig. 6 is a transverse, sectional view showing the canvas with its ribbed portion sewed to an inner sole.

By referring to the drawings it will be **50** seen that my device has an upwardly-extending arm 5, having a slot 6, through which a bolt or screw member 7 may be disposed, by which the arm 5 may be held in position on a sewing machine member 8. At the bottom of the arm 5 the device has **55** a curved portion 9, and a foot member 10, which is normally disposed parallel with

the table 11 of the sewing machine. This foot is provided with a slot 12, the slot being continued rearwardly to the opening 13, in the said curved portion 9 of the device. **60** The device extends upwardly and forwardly from the foot portion 10, and is provided with a bottom member 14, and a top member 15, the top member 15 and the bottom member 14 being connected by sides 16. **65** The top member 15 is provided with a channel 17, so that the ribbed portion 18 of the fabric member may pass through the channel 17, while the side portions 19 of the fabric member may pass through the passageway 20 which extends at each side of the bottom of the channel 17. This channel 17 increases in depth at its forward portion **70** 17^a, and journaled in the sides 16^a of the device there is a dividing member or wheel **75** 21, the sides 22 of which converge toward its periphery 23. Between the dividing member or wheel 21 and the bottom member 14 there is journaled a drum 30, for flattening the side portions 19 of the ribbed fabric **80** member after the said side portions 19 have been separated by the dividing member or wheel 21.

As will be best seen by referring to Fig. 1 of the drawings there are needle holes 24 in **85** the foot 10, at each side of its slot 12.

In using the invention the fabric member **90** 25 having the rib 18 and the side portions 19 is fed into the device at the front end, the wheel 21 serving to separate the side **95** portions 19, when the rib 18 of the fabric member enters the device at the front end 17^a of the channel 17. As the fabric member 25 travels through the device its side portions 19 are spread so that when they **100** come in contact with the drum 30 the drum serves to hold the side portions 19 substantially in alignment with each other. The depth of the channel 17 decreases rearwardly, and the periphery of the drum 30 **105** is disposed in close proximity to the bottom of the said channel 17 so that the side portions 19 of the fabric member 25 are pressed against the drum 30 to spread them, so that they will be in position when they reach the bottom member 14.

As will be best seen by referring to Fig. 2 of the drawings, the device is curved forwardly and upwardly, which assists in separating the side portions 19 of the fabric **110** member 25, and holds them in position. When the fabric member 25 reaches the foot

10, the rib 18 travels in the slot 12, while the side portions 19 are held under the foot 10 and at each side of the slot 12. When in this position the needles 26 on the sewing machine may readily sew the fabric member 25 to the inner sole 27, the needles passing through the needle holes 24 in the foot 10. After the fabric member 25 has been sewed to the inner sole 27 the inner sole, with the 10 fabric member 25 sewed thereto, passes rearwardly, of the machine, the rib 18 passing through the opening 13 in the curved portion 9 of the device.

In the manner indicated, an inner sole 15 may be manufactured, without the necessity of channeling the inner sole to obtain the desired rib, with which to attach the welt and other portions of the shoe thereto. As it is unnecessary to channel the inner soles 20 which are used, very much lighter and cheaper inner soles may be used than is now the case, while, at the same time, the canvas rib 18 forms a much stronger means by which the welt and other portions of the 25 shoe may be attached to the inner sole. This rib 18 is sewed together at 18^a, to limit the spread of the side portions 19 of the fabric member 25.

Having thus described my invention I 30 claim as new and desire to secure by Letters Patent:

1. In a device of the character described, a member having bearings, a wheel journaled in the bearings, and having sides 35 which converge toward the periphery of the wheel, the wheel serving to separate the side portions of a ribbed member, a drum journaled in a bearing in the first-mentioned member for engaging the said portions of the ribbed member, for holding them in substantially the same plane, there being a channel in the first-mentioned member through which the rib may travel.

2. In a device of the character described, a member having a bearing, a wheel journaled in said bearing and having sides which converge outwardly toward its periphery, the wheel serving to separate the side portions of a ribbed member, the first-men-

tioned member having a passageway with 50 sides for receiving the said portions of the ribbed member and a channel disposed at an angle with and between the sides of the passageway, for receiving the rib on the ribbed member, there being needle holes in 55 the member to permit needles to engage the said side portions of the ribbed member.

3. In a device of the character described, a member having a foot with a portion extending from the foot and having a passageway with sides for receiving portions of a ribbed member at each side of the rib and a channel for receiving the said rib, the said portion of the member being disposed forwardly and upwardly from the foot to 60 assist in separating the sides of the ribbed member, and a wheel journaled in the member, the sides of the wheel converging in the direction of the channel.

4. In a device of the character described, a member having a foot with a portion extending from the foot, and having a passageway with sides for receiving portions of a ribbed member at each side of the rib and a channel for receiving the said rib, 75 the said portion of the member being disposed forwardly and upwardly from the foot to assist in separating the sides of the ribbed member, and a drum journaled in the member for holding the sides of the rib 80 member substantially in the same plane.

5. In a device of the character described, a member having a bearing a separating wheel journaled in the bearing for separating the side portions of a rib member, the first-mentioned member having a passageway with sides for receiving the said portions of the rib member and a channel disposed at an angle with and between the sides of the passageway for receiving the 90 rib on the rib member.

In testimony whereof I have signed my name to this specification in the presence of two subscribing witnesses.

FRED L. CORSON.
